UNITED STATES PATENT OFFICE.

RAY G. PARKER, OF DALLAS, TEXAS.

CIRCUIT-CLOSING DEVICE.

Application filed January 31, 1920. Serial No. 355,522.

To all whom it may concern:

Be it known that I, RAY G. PARKER, a citizen of the United States, residing at Dallas, in the county of Dallas and State of Texas, have invented certain new and useful Improvements in Circuit-Closing Devices, of which the following is a specification.

This invention relates to new and useful 10 improvements in circuit closing devices for internal combustion motors.

The aim of the invention is to provide a circuit closing or timing device for controlling the ignition of the charges in the 15 cylinders of the motor and to arrange said device so that no lubricant is required and whereby a dry contact is had; also to provide positive circuit closing and breaking means of a simple and durable nature together with means for excluding oil and other liquids from the device. The result sought is more efficient and reliable ignition with a low cost of maintenance and a long period of service.

25 In carrying out the invention a case or shell is equipped with a plurality of circuit controlling elements in position to be engaged by a wiper carried by the operating shaft and revolved within the case. Means 30 is provided for excluding oil from entering the case and fouling the contact points.

I prefer to employ a circuit controlling element comprising a resilient member formed with a protuberance in the path of the wiper 35 and holding a spring contact away from its contact post, the resilient member having a greater spring tension than the spring contact and the latter being tensioned so as to engage its contact post when released. The 40 resilient member is arranged to release the spring contact when engaged by the wiper and withdraw the spring contact when freed by the wiper, thus breaking the circuit.

The invention will be more readily understood from a reading of the following specification and by reference to the accompanying drawings, in which an example of the invention is shown, and wherein:

Fig. 1 is a cross-sectional view of a device constructed in accordance with my invention,

Fig. 2 is a vertical sectional view on the line 2—2 of Fig. 1, and

Fig. 3 is a perspective detail of the 55 resilient member and the spring contact.

In the drawings the numeral 10 designates a case comprising an annular flange 11 and a cap 12. The flange engages within a ring or annulus 13 cast on the motor 14. At the center of the cap a socket 15 is provided for receiving a pivot point on a suitable retainer (not shown) which is now in common use on Ford automobiles.

At equidistant points on the flange 11, binding posts 16 are mounted and a description of one and its correlated parts will suffice for all. The binding post is screw-threaded and has a flat head 17 at its inner end within the case. The head bears against a shouldered collar 18 seated in an aperture 19 in the flange. A washer 20 on the post bears against the outer side of the flange and the collar. The collar and washer are made of fibre or other suitable insulating material, whereby the post is insulated from the flange. A nut 21 binds the washer and collar together and a second nut 22 is employed to fasten the ignition wire (not shown) to the post.

On the head 17 a contact point 23 is provided and positioned to be engaged by a contact point 24 on the end of a leaf spring 25. The opposite end of the spring is fastened on the offset portion of a bracket 26 secured to the inner side of the flange. A resilient member 27 is fastened on top of the spring by rivets 28 which also pass thru the spring and are secured in the bracket. The member 27 is made of spring metal of a considerably greater tension than the spring 25. This member is bent to form a rounded boss or loop 29 at its free end and terminates in an inwardly directed hook 30 engaging under the outer end of the spring 25.

The member 27 thru its hook 30 holds the spring in a flexed or bent position against its tension and whereby the contact points 23 and 24 are separated and the circuit open or broken. This is the normal position, but it is obvious that when the member 27 is displaced toward the flange 11 the hook 30 will release the spring 25 and the latter will tend to assume a natural or straight position, whereby its contact point 24 will engage the point 23 and close the circuit. Just as soon as pressure is relieved from the member 27 it, thru its superior tension, will swing outward and pull the spring to its flexed position, thus breaking the circuit.

I have illustrated with four circuit controlling elements, but the number may vary. A shaft 30 driven by the motor projects centrally into the case and is shouldered and 5 reduced to receive a collar 31 fastened thereon by a nut 32. The collar carries a radial arm 33 provided with a pair of ears 34 at right angles thereto and between which a wiper block 35 is fastened. The wiper block 10 may be wedge-shaped with its inner end bearing against the collar 31 and its outer and wider end rounded and extending beyond the arm. The bosses 28 of the resilient members 26 are in the path of the block 15 which is revolved with the shaft. It will be seen that the block will readily ride onto the bosses and displace each member thereby permitting the spring 24 to bring its contact 23 into engagement with the contact 20 point 22 of the binding post and close the circuit. As the block rides off of the boss the member 26 will pull the spring back and open the circuit.

It is important that oil be excluded from 25 the case and therefore I mount a disk 36 on the shaft 30 and fasten the same against the shoulder by the collar 31. Within the flange I dispose an annular guard 37 which is dished at its center and formed with an 30 annular trough 39 surrounding the collar and disposed between the disk and the wiper. The guard has a laterally directed flange 38 around its outer periphery and on the opposite side to the trough. This flange 35 38 fits snugly within the flange 11. It will be seen that any oil working along the shaft 30 from the motor 14 will encounter the disk 39 and be confined between the wall of the motor and the guard 37; while any oil

entering at the top between the annulus 13 40 and the flange 11 will be diverted by the flange 38 and pass down the rear side of the guard to the trough 39. Other means of excluding oil could be evolved and the illustration is merely an exemplification. 45

What I claim, is:

In a circuit closing device for internal combustion engines, a casing, a plurality of contacts carried by the casing and insulated therefrom, terminals connected with the contacts, a corresponding number of leaf springs extending circumferentially within the casing in cooperative relation to the contacts and having contact elements to contact with said contacts, means for securing corresponding ends of the leaf springs to the casing, resilient actuating elements extending circumferentially within the casing upon the inner sides of the leaf springs and having corresponding ends thereof secured to the casing in a manner whereby such ends are held against perceptible movement with relation to the casing, said actuating elements being longitudinally curved to provide inwardly projecting cam surfaces provided at their ends with hooks to engage in advance of the leaf springs, said actuating elements being stiffer than the leaf springs and locally yieldable throughout the greater portion of their length and a rotatable 70 wiper arranged to engage said cam surfaces, the wiper having curved engaging surfaces which coact with the longitudinally curved cam surfaces in a manner to gradually depress the actuating elements thereby reducing friction and wear to a minimum. 75

In testimony whereof I affix my signature.
RAY G. PARKER.
